UNITED STATES PATENT OFFICE.

MAX MÜNCH PHIPPS, OF BERNE, SWITZERLAND.

DESIGN FOR AN ARCH-STONE.

SPECIFICATION forming part of Design No. 34,636, dated June 4, 1901.

Application filed June 18, 1900. Serial No. 20,770. Term of patent 34 years.

To all whom it may concern:

Be it known that I, MAX MÜNCH PHIPPS, a citizen of Switzerland, and a resident of Berne, Switzerland, have invented and produced a new and original Design for Arch-Stones, of which the following is a specification, reference being had to the accompanying drawings, forming part thereof.

Figures 1 and 2 are respectively a side and 10 an end elevation of the design according to my invention.

In said design the arch-stone has flat sides $a a'$, and its ends $b b'$ are cut away at an angle with respect to its longitudinal axis. One

side c is convex, while the opposite side c' is 15 concave. It is made with air-compartments d , as shown.

Having thus described my invention, I claim—

The design for an arch-stone substantially 20 as shown and described.

In testimony whereof I have hereunto set my hand in presence of two witnesses.

MAX MÜNCH PHIPPS.

Witnesses:

ERNST P. MÜNCH,
LEVI J. FRANKENTHAL.
